E. F. LOWE,
RAIL CHAIR AND JOINT,
APPLICATION FILED NOV. 17, 1915.
1,215,946.

Patented Feb. 13, 1917.

UNITED STATES PATENT OFFICE.

EUGENE FRANK LOWE, OF DELEVAN, NEW YORK.

RAIL CHAIR AND JOINT.

1,215,946.

Specification of Letters Patent. Patented Feb. 13, 1917.

Application filed November 17, 1915. Serial No. 61,963.

To all whom it may concern:

Be it known that I, EUGENE F. LOWE, a citizen of the United States, residing at Delevan, in the county of Cattaraugus and

5 State of New York, have invented certain new and useful Improvements in Rail Chairs and Joints, of which the following is a specification, reference being had to the accompanying drawings.

10 My invention relates to means for supporting and connecting railroad rails, and particularly to a joint wherein a chair is used for supporting the rails and wherein the rail is supported within the chair by 15 means of rail clamping or engaging members.

Under the present traffic conditions and with increased weight of the rolling stock and the increased speed of trains, it has been 20 necessary to provide some means for supporting a rail upon a tie and clamping rails together at the joint having greater resistance to strain than the ordinary fish plates or spikes. It is further necessary to 25 provide means for preventing the rail from cutting into or wearing away the upper face of the tie, and further to provide means for bracing the rail against lateral or tipping thrust.

30 The primary object of my invention is to provide a rail supporting chair which will meet the conditions above pointed out, which will be cheap to construct, which may be readily applied, and which, when applied, 35 will hold the rail firmly to the tie, brace the rail, and hold two abutting rails in alignment with each other.

A further object of the invention is the provision of a rail joint of this character 40 which will permit the chair to be shimmed without necessitating the detachment of the primary fastenings, spikes, or bolts, and further which will allow for expansion or contraction of the rails.

45 Still another object of the invention is to provide a construction of this character wherein an improved bond may be used between the rails so that electric current may be conducted from one rail to the next, and 50 in this connection to provide means whereby this conductor or bond may be cheaply made, readily disposed in position, and will not get out of place.

55 A further object of the invention is to provide means for limiting the longitudinal

movement of the rails with relation to the chair but permitting a slight longitudinal movement of the rails to provide for expansion or contraction.

Still another object of the invention is the 60 provision of means in connection with the rail engaging and clamping members for preventing the accidental release of the nuts which hold the clamping members in place.

Other objects will appear in the course of 65 the following description.

My invention is illustrated in the accompanying drawings, wherein:

Figure 1 is a view showing my rail chair in elevation and partly broken away, the 70 rail being in section and the tie in elevation;

Fig. 2 is a horizontal section on the line 2—2 of Fig. 1;

Fig. 3 is a perspective view of one of the 75 anchoring plates;

Fig. 4 is a perspective view of one of the bonding plates.

Referring to these drawings, A designates a tie which may be made of any suitable material but is shown as the ordinary wood tie commonly used on railroads. B designates a rail of standard form having the usual base, the vertical web, and the head.

Resting upon the upper face of the tie is 85 the rail chair or base plate, designated 2, which has upstanding flanges 3 at its ends, these flanges being under cut, that is, the inner faces of the flanges extending upward and inward, as at 4. The base plate 2 90 has a width equal to that of the tie, and the middle of the base plate is formed with a slight transversely extending depression, designated 5, within which is adapted to be disposed a copper plate 6 for a purpose 95 which will be later stated. When this plate 6 is disposed in position, the rail rests directly upon it and is approximately flush with the upper face of the base plate 2. The base plate 2 is formed with a plurality 100 of vertical passages 7 for primary fastening bolts, designated 8. These bolts extend downward through the tie A and each pair of bolts on one side of the rail has screw threaded engagement with an anchoring 105 plate 9 which extends transversely of the tie.

Coacting with the base plate 2 and the rail B are the filler blocks or clamping members 10. The inside face 11 of each clamping member is formed to conform to the contour 110

of the web of the rail and the upper face of the base thereof, and the under face of each clamping member rests firmly down upon the upper face of the base plate 2. The outer edge of each clamping member is beveled so as to fit against the under face 4 of the overhanging flange 3 in the manner shown in Fig. 1. Each of these clamping members 10 is cut-away upon its upper face transversely of the tie, as at 12 and each clamping member is provided with a plurality of passages 13 for the passage of bolts 8. These bolts have screw-threaded engagement at their lower ends with the anchoring plates 9 and at their upper ends have screw-threaded engagement with the nuts 15.

In order to prevent the rotation of these nuts 15 in a direction to release the nuts, I may provide any suitable nut lock construction, and preferably I form each clamping member 10 with a pair of inwardly extending bores 16 and dispose in each bore the coiled spring 17 which bears outward on a locking stud 18. This stud is shouldered at its middle so as to provide a portion embraced by the end of the spring and a portion which is engageable with an opening formed in a transversely extending strip 19. This strip has a length equal to that of the corresponding rail clamping member 10. After the nuts 15 have been turned up the studs 18 will be forced inward by any suitable means and the strip 19 dropped into place between the faces of the nuts and the face of the corresponding filler block or clamping member 10. When the studs 18 are released, the studs 18 will be forced out into locking engagement with the corresponding strip 19 and hold it in place against detachment. When it is desired to release either pair of nuts 15, the locking studs 18 are forced inward and the strip withdrawn. This permits the nuts 15 to be turned in a reverse direction.

In order to prevent undue longitudinal movement of the rails with relation to the chair but at the same time permit a certain amount of longitudinal movement to admit of expansion or contraction of the rail, I form each of the rails with the somewhat elliptical openings 20 and form upon the inner face of one of the clamping members 10 the outwardly projecting studs 21 which are adapted to project into the openings 20 in the rails and lock these rails from undue longitudinal movement. These studs, as will be seen from Fig. 2, do not extend entirely through the rail and therefore do not extend entirely through the rail and therefore do not extend into engagement with the other clamping member 10 but only extend nearly through the web of the rail.

In order to provide for the conduction of electric current from one rail to the other rail, I preferably make the plate 6, pre-

viously referred to, of copper. This plate has a width the same as the recess 5 in the upper face of the base plate 2, and this width is greater than the width of the base of the rail so that the rail is supported at 70 its base entirely in contact with this copper plate 6. In order to prevent longitudinal movement of the copper plate 6 with relation to the chair or tie, I form the ends of the plate 6 with the semi-circular lugs or extensions 22 which, as illustrated in Fig. 4, are adapted to be bent down into engagement with the end faces of the plate 2. When it is desired to apply a new plate, these lugs may be readily bent upward, the plate drawn 80 out and a new plate inserted. It will be seen that this manner of applying a conductor to abutting rails is very cheap, very simple, and thoroughly effective.

The bonding plate 6 is fully described and claimed in my pending application, Serial No. 68,024, filed on the 21st day of December, 1915.

It will be noted that the rail engaging members 10 conform on their inner faces to 90 the upper face of the base of the rail and to the conformation of the web and extend upward nearly to the head of the rail. Thus the rail is fully supported along its entire vertical extent, and not merely at the base 95 of the rail as is the case where spikes are used. These rail braces therefore offer maximum resistance to lateral or tipping thrust and securely hold the rail in place without danger of the rail spreading. It 100 will further be seen that by placing shims between the tie and the under face of the base plate 2, the rail will be elevated when necessary, and furthermore, that the rail may be slightly tipped by using more shims 105 on one side of a chair than on the other.

It will be noted that it will be difficult for moisture to enter into the holes formed for the bolts inasmuch as the openings through the clamping members 10 will be protected 110 by the nuts 15, and inasmuch as the base plate 2 covers the entire tie. Thus there will not be so much liability of the wood rotting around the openings for the bolt 8. Furthermore, there will be no necessity of constantly adjusting the rail to gage. Where spikes are used the spikes are continually loosening under the action of passing trains. The holes for the spikes, as a consequence, wear, and the rail has continually to be re-spiked and readjusted. With the rail chair forming the subject of this application, no such constant adjustment will be necessary as the rail will be very firmly and solidly held to the tie, and once set to proper gage 120 will remain so set. Furthermore, it will be seen that the downward pressure exerted by a passing train will be distributed over a large amount of tie surface by reason of the plate 2, and thus the upper face of the tie 130

will not become worn or broken as is the case where rails rest either directly upon the tie or upon relatively small wear plates.

The rail joint heretofore described is simple, may be cheaply made, and the rails may be put in place or removed as quickly with my joint as with the joint in ordinary use.

Attention is also called to the fact that with my improved rail joint the strain due to the tipping thrust upon the rails is not resisted entirely by the nuts 15 but is resisted by the overhanging end flanges which engage with the ends of the rail engaging members. Thus the rail will be held very firmly in position upon the base plate and inasmuch as this base plate has a relatively large area it will be held very firmly upon the tie.

Having described my invention, what I claim is:

1. In a rail joint, a base plate having overhanging end flanges, a tie upon which the base plate rests, bolts passing upward through the tie and through said base plate, and rail engaging members having openings through which said bolts pass and having their ends inserted beneath the overhanging end flanges of the base plate.
2. In a rail joint, a tie, a base plate resting on the tie and having inwardly extending overhanging flanges, bolts passing upward through the tie and through said base plate and constituting primary fastenings, and rail engaging members mounted upon the base plate, the inner faces of the rail engaging members conforming to and fitting on the base of the rail and against the web thereof, the outer edges of said rail engaging members being beveled and extending be-

neath the overhanging end flanges of the base plate, said members having openings for the passage of said bolts.

3. In a rail joint, a base plate, a rail resting thereon and having longitudinally elongated perforations through its web, and oppositely disposed rail engaging members detachably mounted upon the base plate and having portions extending upward on each side of the web of the rail, one of said members having studs projecting through the openings in the rail, the studs being less in diameter than the length of the perforations.

4. In a rail joint, a tie, a base plate resting on the tie and having end flanges extending upward and inward, rail engaging members mounted upon the base plate, the inner faces of the rail engaging members adapted to engage the base and the web of a rail, the outer ends of the rail engaging members fitting beneath the overhanging end flanges of the base plate, anchoring plates disposed on the bottom of the tie, and bolts having screw threaded engagement with the anchoring plates and extending upward through the base plate and through said rail engaging members, nuts having screw threaded engagement with the upper ends of the bolts reversely directed to the screw threads on the lower ends of the bolts, and means for locking the nuts on the upper ends of the bolts from rotation.

In testimony whereof I hereunto affix my signature in the presence of two witnesses.

EUGENE FRANK LOWE.

Witnesses.
